PROCESS FOR PRODUCING AN AROMATIC CONCENTRATE FROM A MIXED HYDRO-CARBON STOCK

William H. Gammon, Ashland, Ky., assignor to Ashland Oil & Refining Company, Ashland, Ky., a corporation of Kentucky

Filed Apr. 15, 1963, Ser. No. 272,954

8 Claims. (Cl. 260—668)

This application is a continuation in part of my pending application Serial No. 85,242, filed January 27, 1961 and now abandoned.

This invention relates to a process for converting a mixed hydrocarbon stock into an essentially pure aromatic concentrate containing a large proportion of bicyclic aromatic compounds and not more than about 5% paraffins.

Recently the refining industry has been provided with highly effective new processing techniques for the production of aromatics, based upon the concept of partially or completely dealkylating alkylaromatics to produce benzene, toluene, xylenes, naphthalene, and heavier compounds. One example of such a process for the complete or partial dealkylation of alkylnaphthalenes to convert them to naphthalene or lower alkylnaphthalenes is described and claimed in Gammon et al. U.S. Patent No. 3,075,022, issued January 22, 1963, entitled "Process for the Production of Naphthalene." By related processing techniques, alkylbenzenes are dealkylated to produce benzene, toluene and xylenes.

For economic reasons, it is desirable that the alkylaromatic feed stocks to be converted by these new processes contain as large a percentage of alkylaromatics as practical and contain only relatively small proportions of paraffins. In actual practice it is preferred that the dealkylation feed stock be at least 95% aromatic. To the extent that paraffins are present in the dealkylation feed, they reduce the efficiency of the dealkylation process by consuming hydrogen needed for the dealkylation reaction, as they are hydrocracked to lighter paraffinic compounds. Moreover, if they are not cracked to lighter materials, paraffins will appear in the dealkylated stock as impurities which are not easily separable therefrom. The availability and desirability of these dealkylation techniques has, therefore, presented a need for an efficient, economically practical process for producing alkylaromatic concentrates, especially alkylnaphthalene concentrates, of low paraffinic content for use as dealkylation feed stocks. The process of this application is intended to fulfill that need.

In principle, it is readily possible to produce aromatics by dehydrogenating naphthalenes. Many naphth and kerosene hydrocarbon stocks contain substantial concentrations of naphthalenes, and from an economic standpoint are logical dehydrogenation feed stocks. However, the naphthalenes in these stocks are invariably mixed with paraffins which complicate the problem of producing relatively pure dealkylatable aromatic concentrates from such stocks by methods other than relatively expensive solvent extraction techniques. Because many of the paraffinic compounds in these dehydrogenatable stocks have boiling points which are close either to those of the naphthalenes with which they are mixed or to those of the alkylaromatics produced by dehydrogenation of the alkylnaphthalenes, it is difficult to separate either the naphthalenes or the resultant aromatics from these paraffins. Undesirably large concentrations of paraffins will, if not removed, appear in the dehydrogenated stock, a result which is undesirable for reasons previously explained when the dehydrogenated stock is to be dealkylated.

Conventional catalytic reforming operations remove the bulk of these paraffins by hydrocracking them to lighter gaseous products which are readily separated from naphthalenes or aromatics. However, the heavier paraffins which are thus converted to gaseous or light hydrocarbons by hydrocracking are themselves valuable materials, and their destruction is economically undesirable. For that reason, conventional catalytic reforming operations are not in general economically satisfactory techniques for producing aromatic concentrates for dealkylation. In the past, in order to obtain an aromatic concentrate of low paraffin content from an impure or mixed naphtha stock, the reforming reaction has had to be conducted at severe process conditions so that substantially all of the heavier paraffins will be hydrocracked to gaseous hydrocarbons and removed. Operating at such severe conditions causes large quantities of coke to be formed which are deposited on the dehydrogenation catalyst and reduce its active life, thereby further disrupting process economics.

20 The situation is even more unfavorable in regard to bicyclic aromatics, that is, naphthene and its alkyl derivatives. As a group, these compounds boil at higher temperatures than the more common single ring aromatics. Paraffins boiling in the range of bicyclic aromatics, being relatively long chain substances, are even more susceptible to hydrocracking than paraffins boiling in the benzene and lower alkylbenzene range. As a result, even heavier production of coke accompanies the dehydrogenation of bicyclic naphthalenes which are 25 admixed with paraffins in a naphtha stock. Heretofore only very short catalyst lives have been obtainable in such processes, and consequently the need for an economical process of producing an aromatic concentrate containing bicyclic aromatics from available bicyclic naphthene-containing stocks has been very pressing.

I have discovered a process for producing aromatic concentrates of large bicyclic aromatic content and of low paraffin content, typically less than 5%, from naphthenic stocks containing paraffins without serious hydrocracking, whereby those paraffins are recovered from the aromatics produced and are available for further use.

Briefly put, the process I have discovered comprises, fractionating from a mixed hydrocarbon feed containing naphthalenes a cut which has an end boiling point between about 400° F. and 450° F. and a 95% point not higher than about 425° F., so that a substantial portion, preferably all, of the bicyclic aromatic compounds obtainable by the dehydrogenation of their naphthenic precursors will boil higher than all but a small portion, preferably 5% or less, of the paraffins in the stock. This cut is then catalytically dehydrogenated at low residence time, high space rate operating conditions, whereby at least a portion of the naphthalenes present in the stock are dehydrogenated to their corresponding aromatics. 55 The dehydrogenated stock is fractionated to produce an aromatic concentrate having an initial boiling point in the range of about 400—420° F., and a lower boiling paraffin-containing fraction. The aromatic concentrate so obtained typically consists of 95% or more mixed mono and bicyclic aromatics, with 5% or less mixed paraffins and unconverted naphthalenes, depending on the nature and the end point of the particular cut selected for dehydrogenation.

By dehydrogenating at low hydrocracking conditions, 65 the dehydrogenation of mono- and bicyclic naphthalenes is accomplished with little scission even of long chain paraffins, with the result that excellent catalyst life is demonstrated. Moreover, because cracking of paraffins is low and the paraffins are subsequently separated from the aromatic concentrate, they constitute a valuable by-product which is available for further use.

In contrast to many past processes, the separation of

the aromatic concentrate by this process does not necessitate a solvent extraction step, and a further economic advantage is thereby effected. In a modification of the basic process, solvent extraction may be utilized to separate those aromatics which are contained in the lower boiling, less aromatic fraction from the paraffins and unconverted naphthenes therein, but because of the smaller quantity of liquids involved that step still involves less expense than a process wherein all of the aromatics are solvent extracted from the dehydrogenated stock.

In the drawing:

FIGURE 1 is a schematic diagram of the process I have discovered; and

FIGURE 2 is a schematic diagram of a modified embodiment of the process.

A typical naphtha stock is primarily a mixture of various paraffins and naphthenes. Some quantities of olefins and aromatics are also present, but usually not in concentrations above about 10%. These compounds boil over a wide range of temperatures which overlaps the lower end of the boiling range of the bicyclic aromatics.

In the preferred practice of this process, a naphtha stock (or an equivalent naphthene-containing hydrocarbon mixture) is fractionated to an end boiling point which is fixed by reference to the composition of the stock so that at least a substantial portion of the bicyclic aromatics obtainable by dehydrogenation of the naphthenes present in the stock will boil higher than substantially all of the paraffins present in the stock. Typically, the concentrations in a naphtha stock of paraffins boiling in the range of the bicyclic aromatics diminish with increasing boiling temperature or molecular weight. In practice, it is not usually possible to obtain a heavy naphtha which contains no paraffins boiling in the range of the bicyclic aromatics, but from an inspection and PONA analysis of a naphtha or kerosene stock it is possible to fractionate a cut containing 5% or less paraffins boiling in the range of the bicyclic aromatics, i.e. above about 420° F. The end point of a heavy naphtha prepared according to these criteria will generally be between 400° F. and 450° F., and also the 95% point of the stock will generally be less than about 420° F. The end point should be as high as is consistent with acceptable paraffinic content of the aromatic concentrate product. Thus, where paraffinic content does not increase substantially with increase in the end boiling point of the cut, fractionation to a higher end point would not cause a large increase in paraffinic content of the final concentrate, yet would effect an increase in the bicyclic aromatic content of the concentrate. The initial boiling point of the cut is not critical, and will depend upon the use to be made of the lower boiling paraffin-containing fraction to be produced following dehydrogenation. However, since the lowest boiling bicyclic naphthene boils at 369° F., some of the bicyclic naphthenes will be eliminated from the dehydrogenation feed stock if the IBP is higher than 369° F., and will therefore not be converted to aromatics.

EXAMPLE I

A typical heavy naphtha selected according to these considerations might comprise, for example, a 345-425° F. cut. The inspection of a typical such feed stock is as follows:

345-425° F. Heavy naphtha

° API	44.9
IBP, ° F.	345
5	359
10	362
20	365
30	367
40	368
50	370
60	373
70	375

80	379
90	386
95	394
EP	425
5	Saturates
	Olefins
	Aromatics

From this data, it can be seen that the stock has essentially no paraffins boiling in the range of the bicyclic aromatics (boiling above 424° F.) and that the proportion of paraffins boiling above 394° F. does not exceed 5%, even assuming all of the highest boiling 5% of the fraction to be paraffinic. Thus, virtually all of the bicyclic aromatics obtainable upon dehydrogenation of this stock will boil higher than the paraffins in the stock. After the reforming step a virtually pure aromatic stock can be separated by fractionating a cut having an initial boiling point of about 420° F., and only a small proportion of paraffins will be included if the initial boiling point of the aromatic concentrate is lowered to 410° or 400° F.

This stock is catalytically reformed or dehydrogenated at high space rate-low residence time conditions. The catalyst may comprise any conventional dehydrogenation catalyst. As an example of the use of a catalyst of the platinum on alumina type, the reforming catalyst sold by Engelhard Industries, Inc., Newark, New Jersey, under their trade designation RD-150, can be used to dehydrogenate the stock with low cracking of paraffins by contacting the stock with a bed of the catalyst in the presence of hydrogen, at a temperature of 820-975° F., a pressure of 100-1000 p.s.i.g., a weight hourly space velocity of about 5-20, and a catalytic residence time of 4-15 seconds.

By dehydrogenating a heavy naphtha fractionated according to these considerations at conditions of low residence time and high space rate, a substantial portion of the naphthenes present in the stock will be converted to their corresponding aromatics without the accompanying destruction of the bulk of the paraffins present.

Following is a particular illustration of the dehydrogenation of the 345-425° F. heavy naphtha of this example:

45	Weight hourly space velocity	11.4
	Temperature, ° F.	924
	Pressure, p.s.i.g.	306
	Gas/oil molal ratio	4.0
	Residence time, seconds	4.8
50	Hydrogen partial pressure, p.s.i.	257
	(Platinum on alumina catalyst, RD-150)	
	Inspection of product:	
	° API gravity	38.0
	ASTM distillation:	
55	IBP, ° F.	140
	10	256
	30	340
	50	371
	70	388
60	90	440
	EP	485
	Saturates	31.4
	Olefins	2.7
	Aromatics	65.9
65	Liquid yield, wt. percent of feed	85.9
	Wt. percent naphthalene precursors expressed as naphthalene	8.2
	Total reformate yield, wt. percent	85.9
70	When naphthenes are dehydrogenated, corresponding aromatics are produced which boil higher than the naphthenes from which they were formed. Thus, in the example given above, although the dehydrogenation feed stock contains no naphthenes, paraffins, or aromatics boiling higher than 425° F., all of the bicyclic aromatics pro-	

duced boil above 424° F., that being the boiling point of naphthalene.

These changes in boiling point are illustrated in typical instances by the following table, in which naphthenes and their boiling points are listed to the left of their corresponding aromatics and their boiling points:

Naphthene	B.P., °F.	Aromatic	B.P., °F.
n-propylcyclohexane	314	n-propyl benzene	319
n-butyl cyclohexane	358	n-butyl benzene	362
trans-decalin	369	Naphthalene	424
cis-decalin	384	do	424
9-methyl trans-decalin	401	(2-methyl naphthalene	466
2-methyl trans-decalin	406	1-methyl naphthalene	473
n-hexyl cyclohexane	435	(2-methyl naphthalene	466
2-ethyl cis-decalin	451	1-methyl naphthalene	473
		n-hexyl benzene	439
		2-ethyl naphthalene	496

From the table it can be seen that, in general, the bicyclic naphthenes jump some forty or more degrees in boiling temperature upon their dehydrogenation to aromatics, and thereby tend to concentrate themselves in a high boiling portion of the reformate. On the other hand, monocyclic naphthenes boiling in the range of the bicyclic naphthenes, or of comparable molecular weights, increase only slightly in boiling point upon dehydrogenation, and do not significantly tend to concentrate themselves in a high boiling portion of the reformate, although some monocyclic naphthenes do boil at temperatures overlapping those at which the bicyclic aromatics boil and therefore upon conversion produce monocyclic aromatics which boil in the range of the bicyclic aromatics.

Following the dehydrogenation step, the liquid product is separated from the gaseous products of dehydrogenation, as is indicated diagrammatically on the accompanying drawing. This may be effected in any conventional manner and need not be described in detail herein. Following separation, this gas may be recycled to the dehydrogenation unit to supply the hydrogen necessary therefor.

The high boiling aromatic concentrate is then separated from the unconverted naphthenes and paraffins (and other low boiling compounds which may be present) by simple fractionation. The dehydrogenated stock is fractionated to yield a high boiling fraction which comprises high boiling alkylbenzenes in admixture with a large proportion of bicyclic aromatics, and a lower boiling fraction which comprises paraffins, unconverted naphthenes, low boiling monocyclic aromatics and other low boiling compounds. The initial boiling point of the aromatic concentrate is critical in respect to obtaining an aromatic concentrate of low paraffin content, as paraffin content increases as the IBP is dropped below about 400° F. The IBP of this fraction should be from about 400 to 420° F.

As an example of the dehydrogenated fractions obtained by this fractionation step, the lower boiling fraction of the dehydrogenated 345-425° F. heavy naphtha of this example shows the following inspection:

°API gravity	42.9
ASTM distillation:

70	363
90	376
EP	401
Saturates	41.6
Olefins	1.6
Aromatics	56.8
F-1 Clear	82.5
Yield, wt. percent of feed	67.0

The 400° F. and higher boiling fraction of the same dehydrogenated naphtha has an °API gravity of 17.5, a 75

mono- and bicyclic aromatic content of 98.6 wt. percent, 1.4% olefins, and substantially no paraffinic content. The yield of this fraction, in terms of weight percent on feed, is 18.9. The yield of naphthalene precursors (bicyclic aromatics) expressed as naphthalene, in terms of weight percent on 400° F. and higher cut, is 43.4.

EXAMPLE II

A 358-438° F. heavy naphtha was selected as the dehydrogenation feed stock. The inspection of this stock was as follows:

10	385-438° F. Heavy naphtha
15	°API 43.0
15	IBP, °F. 385
5	5 390
10	10 392

	Olefins 1.6
30	Aromatics 13.5

This stock was dehydrogenated at conditions as follows:

Weight hourly space velocity	5.8
Temperature, °F.	937
35	Pressure, p.s.i.g. 500
	Gas/oil molal ratio 8.0
	Residence time, seconds 9.0
	Hydrogen partial pressure, p.s.i. 459
	(Platinum on alumina catalyst, RD-150)

40 Inspection of product:

45	°API 35.6
	IBP, °F. 148
5	5 214
10	10 262
20	20 323
30	30 356
40	40 376
50	50 392
50	60 400
	70 413
	80 430
	90 458
	95 485
55	EP 507
	Saturates 35.5
	Olefins 1.5
	Aromatics 63.0
	Liquid yield, wt. percent of feed 85.1

60 This dehydrogenated product was fractionated into a low boiling paraffin-containing cut and an IBP-400° F. higher boiling aromatic concentrate.

65 Inspection of the lower boiling fraction:

65	°API 46.2
	IBP, °F. 117
	10 220
	30 301
	50 348
	70 367
	90 380
	EP 394
	Saturates 54.5
	Olefins 1.9
	Aromatics 43.9

The 400° F. and higher boiling fraction of the reformate had an °API gravity of 20.8, a saturate content of 9.6 wt. percent, an olefin content of 1.4%, and an aromatic content of 89.0%. The weight percent of naphthalene precursors expressed as naphthalene, in terms of weight percent on feed, was 13.0%, or 38.8% in terms of weight percent on cut. In contrast, a 420° F. and higher boiling fraction of the reformate showed negligible saturate content, 1.0% olefins, and 99.0% aromatics. The yield of naphthalene precursors expressed as naphthalene, in terms of weight percent on feed, was 13.0%, or 60.0% in terms of weight percent on cut. This illustrates the criticality of the initial point of the fraction in respect to minimizing paraffin content of the aromatic concentrate.

In the past, it has been the practice to produce aromatic concentrates by reforming naphthenes at severe low space rate, high residence time conditions to hydrocrack paraffins therein as the naphthenes are being dehydrogenated, so that they will not be present in the product. As a typical instance of conventional past practice, the same 385-438° F. heavy naphtha referred to in Example II, upon dehydrogenation at conventional conditions, e.g., a WHSV of 2.9, a temperature of 943° F., a pressure of 511 p.s.i.g., a molal gas recycle ratio of 7.0, a residence time of 21.8 seconds, and a hydrogen partial pressure of 460 p.s.i., yielded a product as follows:

°API	31.0
IBP, °F.	140
10	240
30	328
50	371
70	418
90	473
EP	536

and contained 27.4 weight percent saturates, 3.1% olefins and 69.5% aromatics. Liquid yield was 75.5%, in sharp contrast to the 85.1% yield of reformate shown by Example II. Catalyst life was extremely short.

A 400° F. and lower boiling fraction of this conventional reformate had a saturate content of 38.0%, an olefin content of 2.7%, and an aromatic content of 59.3%. The yield of this fraction, in terms of weight percent on feed, was 48.6%. A 400° F. and higher boiling fraction of this reformate was 98.4% aromatics, 0.6% olefins, 1.0% paraffins, and contained 55.6% naphthalene precursors expressed as naphthalene. The yield of this fraction in terms of weight percent on feed, was 14.9%.

By dehydrogenating a naphtha cut which has been fractionated in accordance with the criteria herein specified at process conditions of high space rate and low residence time, the dehydrogenation reactions take place in preference to the hydrocracking of paraffins, with the result that those paraffins are not materially destroyed and can subsequently be recovered from the dehydrogenated stock simply by fractionation. The total liquid product may be 10% or more larger. This figure of itself indicates less hydrocracking and, consequently, considerably longer catalyst life.

Because these paraffins are not cracked during the dehydrogenation step, they will be present in the dehydrogenated stock. It is for this reason that paraffins boiling in the same range as the bicyclic aromatics must be of low concentration in the dehydrogenation feed stock, so that they will also be of low concentration in the bicyclic aromatic concentrate. Because the bicyclic naphthenes boil about 50 to 80° F. lower than their corresponding aromatics, fractionating the dehydrogenation feed stock to eliminate high boiling paraffins therefrom does not remove an important proportion of the naphthenic bicyclic aromatic precursors.

The lower boiling mixture produced from a naphthene-containing stock by the dehydrogenation process above described will normally contain some single ring aromatics. These aromatics constitute a valuable source of

dealkylatable compounds, and may be removed from that lower boiling fraction by solvent extraction and then be completely or partially dealkylated to produce benzene, toluene or xylene, for example, as described in Paulsen U.S. Patent No. 2,951,886.

EXAMPLE III

Following is a description of a modified embodiment of the process whereby a dealkylation feed stock containing both mono- and bicyclic aromatic compounds is prepared from a full boiling naphtha, as illustrated diagrammatically in FIGURE 2 of the drawings.

A naphtha or other stock containing both single and double ring naphthenes is fractionated to an end boiling point such that a substantial portion of the bicyclic aromatics obtainable upon dehydrogenation of bicyclic naphthenes contained therein will boil higher than substantially all of the paraffins contained therein. This stock is dehydrogenated to convert naphthenes therein to aromatics. After removal of light gases in the dehydrogenated effluent, the liquid product is fractionated to yield at least a higher boiling aromatic concentrate containing a substantial proportion of bicyclics, and a lower boiling fraction which contains monocyclic aromatics, unconverted naphthenes and paraffins. The high boiling aromatic concentrate is charged to a dealkylation unit for conversion to naphthalene.

Aromatics in the lower boiling fraction are separated by a solvent or other extraction process, and are then dealkylated to yield benzene, toluene, or xylenes in accordance with known procedures. The raffinate from the aromatic extraction unit comprises a high concentration of paraffins together with some naphthenes, and may be charged to a dehydrocyclization unit wherein these saturates, or at least some of them, are converted to aromatics. As shown in FIGURE 2, the dehydrocyclized product is recycled to the aromatic extraction unit wherein the aromatics are separated for dealkylation.

By this modification of the process substantially all of the aromatics in a full boiling naphtha are separated therefrom as an aromatic concentrate of low paraffin content from which benzene, naphthalene and derivatives thereof can be produced. The separation of this aromatic concentrate is in part effected by simple fractionation rather than by more expensive solvent extraction techniques, which is a distinct economic advantage.

While I have described the preferred embodiment of my process herein, it will be understood that it is susceptible of variations and modifications falling within the scope of the claims which follow:

Having described my invention, I claim:

1. A process for producing an aromatic concentrate containing a large proportion of bicyclic aromatics and less than 5% of paraffins, which comprises fractionating a mixed hydrocarbon stock containing paraffins and bicyclic naphthenes to produce a fraction having an end boiling point between about 400 and 450° F. and a 95% point no higher than about 425° F. so that a substantial portion of the bicyclic aromatic compounds obtainable upon dehydrogenation of the bicyclic naphthenes in said fraction boils higher than all but a small portion of the paraffins present in said stock, dehydrogenating said fraction over a dehydrogenation catalyst to convert at least a portion of the bicyclic naphthenes therein to the corresponding aromatics, and fractionating the dehydrogenated fraction to produce a substantially aromatic concentrate having an initial boiling point above about 400° F. and a paraffin content less than 5% and a lower boiling paraffin-containing fraction.

2. A process according to claim 1, in which the mixed hydrocarbon stock comprises a petroleum naphtha.

3. A process according to claim 1, in which the mixed hydrocarbon stock is fractionated to produce a fraction having an end boiling point between about 435 and 450° F.

4. A process according to claim 1, in which the mixed hydrocarbon stock is fractionated to produce a fraction having a 95% point between about 420 and 425° F.

5. A process according to claim 1, in which the mixed hydrocarbon stock is fractionated to produce a fraction so that a substantial portion of the bicyclic aromatic compounds obtainable upon dehydrogenation of the bicyclic naphthalenes in said fraction boils higher than all but less than 5% of the paraffins present in said stock.

6. A process according to claim 1, in which said fraction is dehydrogenated over the dehydrogenation catalyst at conditions of low residence time and high space rate with only minor cracking of paraffins.

7. A process according to claim 1, in which the dehydrogenated fraction is fractionated to produce a substan-

tially aromatic concentrate having an initial boiling point between about 400 and 420° F.

8. A process according to claim 7, in which a substantially aromatic concentrate having an initial boiling point of about 420° F. is produced.
